CLAIM

The ornamental design for a case for a mobile device, as shown and described.

DESCRIPTION

FIG. 1 is a perspective front view of a case for a mobile device showing our new design.

FIG. 2 is a perspective back view of the case for a mobile device.

FIG. 3 is an elevational front view of the case for a mobile device.

FIG. 4 is a top plan view of the case for a mobile device.

FIG. 5 is a bottom plan view of the case for a mobile device.

FIG. 6 is an elevational right side view of the case for a mobile device.

FIG. 7 is an elevational left side view of the case for a mobile device.

FIG. 8 is a perspective front view of the case for a mobile device; and,

FIG. 9 is a perspective back view of the case for a mobile device.

The broken lines in the drawings are for the purpose of depicting parts of the case for a mobile device that form no part of the claimed design.

1 Claim, 7 Drawing Sheets
